(57) **CLAIM**

The ornamental design for a gift box support, as shown and described.

DESCRIPTION

FIG. 1 is a front and top perspective view of a gift box support showing our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is perspective view of a gift box when the gift box support is placed inside.

The broken lines in the drawings depict portions of the gift box support that form no part of the claim design. The broken lines shown in FIG. 8 depict environmental structure only and form no part of the claimed design.

1 Claim, 8 Drawing Sheets
